UNITED STATES PATENT OFFICE.

CHARLES E. BALL, OF PHILADELPHIA, PENNSYLVANIA.

REGULATOR FOR ELECTRIC LIGHTS.

SPECIFICATION forming part of Letters Patent No. 249,872, dated November 22, 1881.

Application filed February 17, 1881. (No model.)

To all whom it may concern:

Be it known that I, CHARLES E. BALL, a citizen of the United States, residing at the city of Philadelphia, in the State of Pennsylvania, have made certain new and useful Improvements in Regulators for Electric Lights; and I do hereby declare that the following is a full, clear, and exact description of the same, reference being had to the accompanying drawings, forming part of this specification, wherein—

Figure 1 is a vertical elevation, and Fig. 2 a detail plan.

My invention has for its object to provide means for automatically feeding the carbons or electrodes of electric lights toward each other as they consume or waste away, so as to maintain as nearly as is possible a continuous permanent voltaic arc.

My improvements consist in the peculiar construction and combination of parts hereinafter specified, having reference principally to the combination, with two electro-magnets in the path of the light-circuit, or in a shunt thereof, of two shoes or clamps for holding the upper carbon, said magnets being sustained upon a yoke - spring and arranged with their unlike poles facing one another, and said shoes being supported upon the opposing faces or ends of said magnets and adapted to clamp the upper carbon between them, while allowing said carbon to drop or feed and be lifted, as hereinafter more fully set forth.

My improvements still further consist in certain details of construction and combination hereinafter more fully set forth.

Referring to the accompanying drawings, A indicates the frame of an electric lamp, and B and C carbons or electrodes sustained thereto in, end to end, the lower carbon, B, being stationary, while the upper one is movable, as hereinafter set forth.

E represents a bow or yoke spring, fastened at or about its middle by screws e e to the frame A, allowing its ends e' e' to depend, as shown; or, if desired, two springs (which would be represented by cutting the spring E in twain at its middle) may be substituted for the single spring E. Upon either end e' e' of the spring E are sustained electro-magnets F G,

wound in like directions, so as to have their dissimilar poles opposed, in order that when the electric current passes into them they will be attracted toward each other. Said spring E is so bent that its tendency is for its ends to 55 spring apart, thus separating the magnets when no current passes through the latter.

H and I represent shoes, jointed at h and i to stems h' i', hinged at h' i' to the magnets F G, respectively. Said shoes, when the magnets are attracted toward each other by the passage of the electric current, tightly clamp the carbon electrode C between them and hold it in a fixed position, as shown in full lines in Fig. 1. When, by reason of the failure of the 65 are, the current does not circulate, the magnets, ceasing to attract, are drawn apart by the spring, thus causing the shoes to relax their hold on the carbon in their grasp, whereupon the latter drops until it touches the lower carbon, B. This re-establishes the circuit, causing the magnets to be attracted toward each other and the shoes to clamp upon the carbon C. The magnets, as they move toward each other, change the inclination of the stems h' i', 70 thus giving a rising movement to the shoes, whereby the latter lift the carbon C, drawing it away sufficiently from the lower carbon, B, to produce the voltaic arc. The cores of the magnets are shown prolonged sufficiently to 75 come in contact when attracted, a semicircular groove being made in each, forming an opening, k, through which the carbon C passes, and in which it may be held, if desired, said cores thereby acting as an auxiliary clamp. 80

L are arms, provided with set-screws l l, which form stops for limiting the movement of the branches of the spring E. By adjusting these screws the extent of lift of the shoes H I may be regulated, as it is obvious that the farther out the arms of the spring E are permitted to expand the lower down will the shoes take hold of the carbon, and the farther will they lift the carbon when the magnets are attracted toward each other.

The course of the current may be as shown by arrows in the drawings. Thus it may enter at binding - post x, thence pass through electrodes, thence to magnets G F, and finally to binding-post y.

What I claim as my invention is—

1. In an electric-light regulator, the combination, with the electrode C, a spring, E, having electro-magnets F G sustained upon either end thereof, with their dissimilar poles opposed, said spring tending normally to separate said magnets, the latter being designed and operating to be attracted toward each other when an electric current passes through them, substantially as shown and described.
2. The combination, with electro-magnets F G, sustained upon either end of a spring, E, of shoes H I, having stems h' i' , and secured to said magnets, substantially as shown and described.

3. In combination with spring E, sustaining the magnets F G, the latter supporting shoes H I, the adjusting-screws l in arms or supports L, for regulating the lift of said shoes, substantially as shown and described.

In testimony that I claim the foregoing I have hereunto set my hand this 8th day of February, 1881.
